UNITED STATES PATENT OFFICE

ROGER DUBUSC AND AVRAM DAVID ILIOVICI, OF PARIS, FRANCE, ASSIGNEES TO COMPAGNIE POUR LA FABRICATION DES COMPTEURS ET MATERIEL D'USINES A GAZ, OF MONTROUGE, SEINE, FRANCE, A JOINT STOCK COMPANY OF FRANCE

SELECTIVE CIRCUIT PROTECTING DEVICE

Application filed April 15, 1930, Serial No. 444,536, and in France April 30, 1929.

Several devices based on the use of the negative or the zero phase sequence components of the currents, voltages or powers have already been proposed for protecting a 5 circuit.

Pilot wires have likewise been used in selective protection systems and in particular the pilot wires have been used as conductors in the auxiliary circuit, the current of which 10 flows through the trip coils of the circuit-breakers or intermediate relays.

The present invention is concerned with devices in which pilot wires for transmitting the current of the auxiliary sources are used 15 in conjunction with devices for obtaining the negative or zero phase sequence components.

By combining the pilot wires with the filter circuits for obtaining the negative or zero 20 phase sequence components, a more accurate and flexible selection is obtained than when the currents or powers of the circuits are used directly; in addition, as only direct current generally flows through the pilot wires, and, 25 moreover, only for the very short length of time necessary for operating the circuit-breakers, it will nearly always be possible to avoid designing special pilot wires, and telephone wires or any other wires at hand may 30 be used.

Several embodiments of the invention have been illustrated in the accompanying drawings in which:

Fig. 1 illustrates a protecting device for a 35 plurality of feeders in series.

Fig. 2 shows a protecting device for a circuit comprising feeders in parallel and groups of feeders in series.

Fig. 3 shows a protecting device which differs from that of Fig. 2 in that the negative or zero phase sequence component of the current or power flows in one direction only.

Figs. 4, 5, 6 and 7 illustrate further modifications of devices for protecting electric 45 circuits.

In Fig. 1, BO_1 , BO_2 , BO_3 , BO_4 designate the bus-bars of the power station or of the sub-stations; F_1 , F_2 , F_3 are three three-phase feeders following one after another; D_1 , D'_1 , 50 D_2 , D'_2 , D_3 , D'_3 the circuit-breakers of said

feeders (it has been assumed that there is one circuit-breaker at each end), but certain of the circuit-breakers may be cut out. B_1 , B'_1 , B_2 , B'_2 , B_3 , B'_3 are the trip coils of the circuit-breakers which may be replaced by auxiliary relays; f_1 , f_2 , f_3 are pilot wires through which flow the currents produced by the auxiliary sources SA_1 , SA_2 , SA_3 ; F is a return wire for the currents of the pilot wires (the wire F may be replaced by the earth); RW_1 , RW_2 , RW_3 are wattmetric relays (responsive to the negative or zero phase sequence components of power) of the double-throw type. In these relays e_1 is the current winding of the relay RW_1 fed by the secondaries of the three current transformers t_1 mounted in parallel; e'_1 is the voltage winding of the same relay fed by the three reactance, resistance or capacity windings r_1 , r'_1 , r''_1 . The winding e_1 receives the earth current (resultant of the currents in the three phases) and e'_1 a current proportional to the zero phase sequence component of the voltage. The reference characters e_2 , e'_2 , t_2 , r_2 , r'_2 , r''_2 ; e_3 , e'_3 , t_3 , r_3 , r'_3 , r''_3 have the same meaning in connection with the relays RW_2 and RW_3 as the corresponding preceding reference characters.

The wattmetric relays are so arranged that the contact of each relay will close to the left (at 1) when the negative or zero phase sequence component of the power, according to the case in point, in the corresponding feeder is directed towards the right.

In order to make the operation of the device readily understandable, it will be assumed that there is an earth fault at M ; it will likewise be assumed that the relays RW_1 , RW_2 , RW_3 are earth relays and that there are at least two earths, one at T_1 , and the other at T_2 .

It is known that the zero phase sequence power component is always directed from the faulty point towards the earths: hence it will have the direction of the arrows f in the feeder F_1 and in that portion of the feeder F_2 which lies to the left of the point M , and the opposite direction (arrows f') to the right of M . The consequence is that the contacts of the relays RW_1 and RW_2 will close to the

right (at 2) whereas the contacts of the relays RW_3 and RW_4 will close to the left (at 1). It will be readily understood that the circuit of the auxiliary source SA_2 is closed, which 5 will cause the circuit-breakers B_2 , B'_2 to trip, while the circuits of the sources SA_1 and SA_3 will remain open.

Fig. 2 shows the diagram of the same device as that of Fig. 1 applied to the more complex 10 case of a circuit comprising feeders in parallel and groups of feeders in series. In this and in the following figures, in order to avoid overcrowding, the coils of the relays have not been illustrated but they are of course the 15 same as those shown in Fig. 1.

Only one wire of each feeder has been illustrated, and it has been assumed that there are 20 two earths at T_1 and T_2 . The feeders F_1 , F'_1 , F''_1 are in parallel; the feeders F_2 and F'_2 are independent; the first is continued by two 25 independent feeders F_3 and F'_3 . The feeder F'_2 is continued by two feeders F''_3 and F'''_3 in parallel. As in Fig. 1, fp_1 , fp'_1 ... illustrate pilot wires which transmit the currents 30 of the auxiliary sources SA_1 , SA_2 ; the latter are not placed, as in Fig. 1, in the pilot wires, but in the wires which connect the points common to the movable contacts of the relays 35 to the common return wire F ; the other reference characters have the same meaning as in Fig. 1. The advantage of locating the auxiliary sources in the manner shown is that their number is reduced. It will be observed furthermore that only one auxiliary source is 40 used for two sub-stations. Obviously, one source could be used for each station, each source would then only furnish half the voltage to be provided in the case of Fig. 2.

If batteries are used, the number of units 45 for the whole network is the same whether one source per station or one source per two stations be used. It will be observed that there are two circuit-breakers per feeder and two wattmetric relays, save in the case of the 50 feeders F_3 and F'_3 where one circuit-breaker and one relay per feeder has been provided. For the latter feeder, two relays with one or two circuit-breakers, or two circuit-breakers with a single relay might have been used.

55 In reality, there is one relay such as RW_2 for two feeders having a common end. The current coil of this relay may be fed with the current of the one feeder or the other; practically, there will be preferably one relay for each end of each feeder, as will be seen in Fig. 7.

To understand the operation of the device, it will be assumed in the first place that a 60 fault occurs at A , then that the fault is at B , finally at C .

If the fault be at A , the zero phase sequence power component flows in both directions in the feeder F''_1 and in one direction only in all the other feeders. From what has been 65 seen in the case of Fig. 1, the relay RW''_1 will

close its contact at 2, while the contact of the relay RW''_2 will close at 1. The current from the source SA_1 will pass through the windings B''_1 and B''_2 and the circuit-breakers D''_1 and D''_2 will trip. On the other hand, 70 in the other feeders, the contacts of the relays corresponding to the same feeder will close to the same side and the circuits of the corresponding pilot wires will remain open. If the fault occur at B , on the feeder F'''_3 , the 75 same conditions will obtain for this feeder as for the feeder F''_1 in the preceding case and the two circuit-breakers between which it is confined will trip.

If the fault occur at C , the zero phase sequence power component to the right of C will be nil while in the portion of the feeder F'_3 situated to the left of C , the power will be directed towards the left and the circuit-breaker D'_3 will trip. In the feeder F_3 , the 80 zero phase sequence power component will be nil because this feeder includes no earth; consequently its relay RW_3 will remain open. Were there an earth at the right end of this feeder, the power flowing through it would 85 go towards the earth and wattmetric relay RW_3 would deflect to 1 while the pilot wire fp_3 would always remain open. Similar results would be obtained with negative phase 90 sequence power components, whether the neutral of the feeders be insulated or earthed, the fault occurring between two wires in the first case and between two wires or with the earth in the latter case.

95 Fig. 3 illustrates the circuit arrangement 100 corresponding to the case in which the zero phase sequence current or power component only proceeds in one direction; this would be the case should only one earth obtain for example at T . In the case of a fault at a 105 point M , the zero phase sequence current component only exists to the left of M and the zero phase sequence power component proceeds from M to T .

110 In lines in which the neutral is earthed, and assuming that there is a contact between two wires at M , similar conditions to the preceding ones for the negative phase sequence current or power component will prevail, if the line be open to the right of the fault, so that 115 in this portion, there will be neither generators nor receivers (infinite impedance with respect to the negative phase sequence current component).

120 In Fig. 3, it has been assumed that the relays are responsive to the zero phase sequence component and that there is a single earth at T . The various reference characters have the same meaning as in Figs. 1 and 2 but the relays RW_1 , RW_2 ... may be 125 wattmetric or current relays.

130 In the former case, they must deflect to the right when the power proceeds to the left. In the latter case, the flow of current through the relay must make the latter deflect to the

right. It will be observed that the relays are normally closed to the left (at 1).

- If a fault occur at a point, the current flows through the feeders, or feeder sections lying 5 on the left of the fault (between the faulty point and the earth) and does not flow through the others. Thus, for example, if the fault occur at M, the current only flows in the relay RW_1 which deflects to the right and closes 10 the circuit of the windings B_1, B_2 , while the other auxiliary circuits remain open. If the fault occur at M' on the feeder F'_2 , the relays RW_1, RW'_2 deflect to the right, and it will be readily seen that only the circuit of 15 the winding B''_2 is closed.

Figs. 4 and 5 show circuit arrangements in which it has been assumed that the negative or zero phase sequence power component may proceed now in one direction, now in the 20 other, now in both simultaneously, this corresponds to the most general case of a network operating under changing working conditions.

The case of a network with earthed neutral 25 in which the position of the earths is variable will be considered.

In the two figures, there are associated with each feeder two pilot wires $fp_1, fp'_1; fp_2, fp'_2, fp_3, fp'_3$ and a return wire F which 30 may be replaced by the earth. In Fig. 4, it is assumed that the coils of the circuit-breakers have a double winding or that the circuit-breakers have two coils. In Fig. 5, the circuit breakers B_1, B_2 have single windings, but 35 intermediate relays $A_1, A_{11}, A_2, A_{22} \dots$ grouped in pairs with their contacts in parallel are utilized.

In both figures, the reference letters have the same meaning as in the preceding figures; 40 in addition, in Fig. 5, $A_1, A_{11}, A_2, A_{22} \dots$ designate the intermediate relays having contacts C_1, C_{11}, C_2, C_{22} . It will be observed moreover that in Fig. 4, there is one auxiliary source for two stations, whereas in Fig. 5 45 there is one source per station.

The operation of the device is readily understandable. If, in the circuit arrangement of Fig. 4, a fault occur at a point M, three cases present themselves: 1. If there be 50 only one earth at the left end, the contacts of the relays RW_1 and RW_2 will close at 2, whereas the positions of the contacts of the other relays will remain unchanged; it will be seen that in this case, only the circuit of 55 the coils B'_2 and B_3 is closed, whereby the circuit-breakers D'_2 and D_3 will trip; 2. The earth is at the right end; in this case, the current only flows to the right of M and the relays RW'_3 and RW'_4 close their contacts to 60 the left; it will be seen that only the circuit of the windings B'_{22} and B_{33} is closed; 3. Earths exist at both ends; in this case, the relays RW_1, RW'_1, RW_2 and RW'_2 close their contacts to the right, while the others close 65 their contacts to the left (here all the relays

are assumed to be wattmetric and to deflect to the left if the power goes to the right); it will be seen that only the circuits of the windings B'_2, B_3 and B'_{22}, B_{33} are closed; hence the same circuit-breakers D'_2 and D'_3 70 as in the preceding cases will trip.

In the case of Fig. 5, the same three cases have to be considered, but here the closing of the circuits fp_2 or fp'_2 will cause the current to flow in the windings $A'_2, A'_{22}, A_3, A_{33}$ of 75 the intermediate relays, thus closing the contacts $C'_2, C'_{22}, C_2, C_{33}$ which will cause the current to pass through the windings B'_2 and B_3 .

If there be only one auxiliary source for 80 all the stations, an additional pilot wire must be used so that the two poles of the source may be utilized at each station. Fig. 6 illustrates a circuit arrangement similar to that of Fig. 4 save that only one auxiliary source 85 SA obtains. The reference letters have the same meaning as in Fig. 4, but there obtains in addition the wire F' which in conjunction with the wire F enables the two poles of the source to be used throughout. 90

In the preceding devices, it has been assumed that each of the wattmetric relays save those at the ends, serves to protect two feeders starting from the same bus-bars. Thus, the relay RW_2 of Fig. 1 serves for the feeders F_1 and F_2 ; similarly, the relay RW'_2 of Fig. 2 serves for the feeders F'_1 and F'_2 . This arrangement which is economical may become faulty and it is preferable that each 95 wattmetric relay should only serve for a given feeder. Moreover, in the more general types of protective devices, such as those corresponding to the circuit arrangements of Figs. 4 and 5, at each feeder end, a single wattmetric relay having a centrally positioned 100 double contact and two auxiliary relays with contacts pressed against their stops may be used instead of two wattmetric relays with contacts pressed against their stops. 105

Fig. 7 illustrates a circuit arrangement 110 similar to that of Fig. 5 in which the feeders are protected independently of one another with wattmetric and auxiliary relays.

In this figure, $D_1, D_2 \dots$ illustrate the circuit-breakers mounted in the feeders $F_1, F_2, 115 F_3; B_1, B_2 \dots$ the coils of the circuit-breakers; $fp_1, fp'_1 \dots$ the pilot wires, FF the common return wire or the earth; $RW_1, RW_2 \dots$ wattmetric relays with two contacts 1 and 2; $RA_1, RA'_1, RA_2, RA'_2 \dots$ auxiliary relays. The 120 relays RA_1, RA_2, RA'_2 have their contacts thrown over against the lefthand stops and deflect to the right when current flows, while the relays $RA'_1, RA'_2, RA'_2 \dots$ have their contacts thrown over against the righthand 125 stops and deflect to the left when current flows through their windings.

The relays $RW_1, RW_2 \dots$ close the contact 1 when the zero or negative phase sequence power component is directed to the 130

left in the feeders F_1 , F_2 , F_3 , and close the contact 2 if the power is directed in the opposite direction. It will be observed that now the positive, now the negative pole of the auxiliary sources is connected to the return wire F_1 .

The mode of operation of the device is readily understandable. Let a fault occur at M and let the relays be responsive to the zero phase sequence power component.

If there be a single earth at T_1 , the power is directed to the left in the feeder F_1 , and in the portion of the feeder F_2 lying to the left of M , while no power passes to the right of M . The relays RW_1 and RW_2 close their contacts 2, so that the contacts of the auxiliary relays RA_1 and RA_2 move over to 2 and the pilot wires fp_1 and fp'_1 remain open. Similarly, the pilot wires fp_3 and fp'_3 remain open because the relays RW_3 and RW_4 do not act. On the other hand, the relay RW'_2 deflecting to the right closes the contact of RA'_2 at 2, whereby the circuit of the pilot wire fp_2 is closed and current passes through the windings B'_2 and B_3 thus causing the circuit-breakers D'_2 and D_3 to trip.

It will be seen similarly that if the earth is at T_2 , it is the pilot wire fp'_2 which is closed; if the two earths T_1 and T_2 exist simultaneously, the two pilot wires fp_2 and fp'_2 are closed.

In the various devices indicated, the relays may be instantaneous. However, in practice it will be preferable slightly to retard certain of the relays so as to avoid untimely operation.

If wattmetric or current relays are used alone, they will be slightly retarded. When using auxiliary relays, only the latter might be retarded. In all the devices, the windings B_1 , B_2 , B_{11} . . . may be windings of intermediate or auxiliary relays acting on the windings of the circuit-breakers.

We claim:

- 45 1. In a selective protective system for an alternating current network, the combination of a plurality of relays, means for rendering said relays responsive to the negative or zero symmetrical phase sequence component of the power or current of said network, a plurality of circuit-breakers mounted in said alternating current network and including trip coils, auxiliary sources of current, a plurality of auxiliary relays, pilot wires adapted to convey current from said auxiliary sources both to said trip coils and to said auxiliary relays, and two sets of switch means operated by said first mentioned relays and said auxiliary relays respectively for closing circuits for said auxiliary relays and trip coils respectively through said pilot wires.
- 50 2. In a selective protective system for an alternating current network, the combination of a plurality of relays, means for rendering said relays responsive to the negative or zero phase sequence component of the current flowing in each feeder, or of the tension between two feeders, a plurality of circuit-breakers mounted in said alternating current network and including trip coils, auxiliary sources of current, a pilot wire for each feeder adapted to convey the current of said auxiliary source to said trip coils, and means controlled by said relays for making or breaking the circuits of said trip coils through said auxiliary sources depending on the direction of the phase sequence component of the current or tension influencing the relays.
- 55 3. In a selective protective system for an alternating current network, including a plurality of feeders, the combination of a plurality of relays, one at each end of each feeder, means for rendering said relays responsive to the negative or zero phase sequence component of the current flowing in each feeder, or of the tension between two feeders, a plurality of circuit-breakers mounted in said alternating current network and including trip coils, auxiliary sources of current, a pilot wire for each feeder adapted to convey the current of said auxiliary source to said trip coils, and means controlled by said relays for making or breaking the circuits of said trip coils through said auxiliary sources depending on the direction of the phase sequence component of the current or tension influencing the relays.
- 60 4. In a selective protective system for an alternating current network, including a plurality of feeders, the combination of a plurality of relays, one at each end of each feeder, means for rendering said relays responsive to the negative or zero phase sequence component of the current flowing in each feeder, or of the tension between two feeders, auxiliary sources of current, a plurality of circuit-breakers mounted in said alternating current network and including trip coils, pilot wires connecting said trip coils to said auxiliary current sources and two-way acting contact makers operated by said relays respectively in one direction or the other depending on the direction of the symmetrical phase sequence component of the current or tension influencing said relays, for making or breaking the circuits of said trip coils through said auxiliary sources.
